UNITED STATES PATENT OFFICE.

JOHN GEORGE GOLL, OF NEW ROCHELLE, AND PAUL JOHN SOWADA, OF YONKERS, NEW YORK, ASSIGNORS TO WELTE-MIGNON CORPORATION, OF NEW YORK, N. Y., A CORPORATION OF NEW YORK.

PNEUMATO-ELECTRIC DEVICE.

Application filed December 10, 1923. Serial No. 679,820.

To all whom it may concern:

Be it known, that we, JOHN GEORGE GOLL and PAUL JOHN SOWADA, citizens of the United States, residing at New Rochelle, 5 Westchester County, and Yonkers, Westchester County, respectively, State of New York, have invented certain new and useful Improvements in Pneumato-Electric Devices, of which the following is a specification.

This invention relates to pneumato-electric devices and particularly to those pneumato electric devices adapted to control an electric circuit from a perforated tracker.

15 In musical instruments, particularly pipe organs, it has been found that the perforated tracker, the perforations of which are controlled by a perforated music record, is a very satisfactory means of selecting the 20 notes to be played and for controlling the expression devices of the instrument. At the same time, great difficulty has been experienced in producing a control means for the notes to be operated at some distance 25 from the tracker, and which will be operated so short a time, after the opening of the tracker duct, that there is no distortion of the music. In order to transmit an impulse to a distant point, electricity has been found 30 to be the most satisfactory medium.

The primary object of the present invention is to provide an improved pneumato-electric means whereby an electric circuit may be controlled from a primary pneumatic 35 located adjacent the tracker, whereby the advantages of both the pneumatic tracker and the electric control are obtained.

Another object of this invention is the provision of a positive circuit closing device 40 in position to be operated by the primary pneumatic.

Another and further object of our invention is the provision of a primary pneumatic arranged adjacent the terminals of the electric circuit to be controlled and having an 45 intermediate resilient circuit closing device in position to be operated by the pneumatic.

Another and further object of this invention is the provision of a simple pneumato-electric control unit which is readily capable 50 of being installed or removed from its operating position in the tension chamber for alteration or repair.

Referring to the drawing wherein a preferred embodiment is illustrated, 55

Figure 1 is a cross sectional view of the device arranged in a tension chamber,

Figure 2 is a cross section on the line 2—2 of Figure 1,

Figure 3 is a cross sectional view on the 60 line 3—3 of Figure 1,

Figure 4 is a view similar to Figure 1 but with the pneumatic operated to close the circuit,

Figure 5 is a front view showing one of 65 the pneumatics in operated position.

10 designates a wind chest having a tension chamber 11 which in the present instance is under exhaust tension. One side 12 is preferably made of glass in order to 70 aid in the inspection of the operation of the pneumatics and circuit closing devices and to assist in detecting trouble.

Attached to the rear wall 13, by machine screws 14, is the pouch rail 15. The machine 75 screws 14 have a threaded engagement with nuts 16 in the rear of the rear wall 13.

The pouch rail 15 is provided with a series of depressions 17 to form the flush chambers for the pouches 18 of the primary 80 pneumatics. On the top of each of the pouches 18 is a button 19.

Secured to the outer edge of the pouch rail 15 is a contact strip 20 carrying the metallic resilient contact making members 21. At 85 the inner end of each contact making member 21 is an angular portion 22, the lower end of which engages the button 19 and the upper end of which closes the circuit in a manner to be described. This contact making member is made of very thin resilient metal and of sufficient width to insure the operation of the movable end in a proper manner. At the side of the pouch chamber 17 is a duct 23 leading outward through the 95 rear board 13 to connect to a flexible tube 24 which extends to the tracker (not shown).

Rearward of the pouches and supported on the pouch rail 15, by the supports 25, is 100 a contact-supporting board 26. A rib 27 on the lower edge of the board 26, serves to position the contact carriers 28 which are glued or otherwise secured to the board 26. The contact carriers 28 are provided with two 105 contact wires 29 arranged in slots 30. These

contact members are normally on the bottom of the slots, the rear ends being arranged at 90 degrees and passing through small holes as shown on Figure 1 at 31. These 90 degree portions hold the forwardly extending portions normally in place. The ends of the forwardly extending portions of the contact wires, 29, project over the angular portions 22 of the contact making member 21 and in position to be engaged by the same when the pouch is inflated.

At the forward edge of the board 26 is a strip 32 carrying a felt 33. When the contact wires 29 are raised by the inflation of the pouch 18, the wires 29 are pressed against the felt 33, thereby preventing any noise and insuring proper contact between the contact wires 29 and the contact member 22.

Screws 34 hold the board 26 and the supporting member 25 on the rail 15.

At the rear of the contact carriers 28 is a wire 35 extending the length thereof to which one of each pair of contact members 29 is secured and which forms a bus-bar. The other one of each pair of the contact wires 29, goes to a bundle of wires or cable 36 which extends outward through the wall of the wind chest 10 and leads to the sound or expression mechanism as desired.

It is to be understood that while one rail 15 is shown in the drawing, as many as desired may be used, the tension chamber being made of the required height to provide sufficient space.

In order to exhaust the air from the chamber 17, a suitable bleed as 37 may be provided. This bleed is connected by a passage 38 leading to the pouch chamber 17. The bleeds in this construction are at a place where observation, through the window 12, is possible.

The operation is as follows:—

When the perforation of the record sheet (not shown) opens its duct in the tracker (not shown), the air enters the duct 24, and passes through the duct 23 to the chamber 17. This places atmospheric pressure below the pouch 18. As there is exhaust tension above the pouch 18, the latter is caused to be raised, lifting with it the button 19 and the outer end 22 of the contact making member 21, thus causing the outer edge of the end 22 to complete electric communication between the contact wires 29 and operating the magnet (not shown) at the note speaking or expression controlling device, as the case may be.

Air is continually being exhausted from the bleed 37 into the tension chamber 11. This bleed is, however, small compared with the inlet from the tracker and consequently has no effect upon the result. As soon as the supply of air from the tracker duct is cut off by the end of the perforations, the

bleed 37 permits the air beneath the pouch 18 to be exhausted, thereby permitting its collapse and the consequent return of the resilient contacting member 21 to its lower position. This breaks the electric connection 70 between the wires 29.

With this structure, it is possible to obtain a sure and practically instantaneous operation of a note sounding device to be operated even though it is located at a great distance from the selector. At the same time, the use of the ordinary pneumatic tracker with all of its advantages, is permitted.

While one embodiment of this invention has been shown and described in detail, it is 80 to be understood that its use is not limited to the embodiment shown and described and that modifications and changes may be made without departing from the spirit of the invention and within the scope of the appended claims.

Having described a modification of the invention, what is claimed is:—

1. In combination, with a musical instrument, a support, a primary pneumatic, a resilient electric contact member adjacent the pneumatic, and a circuit controlling device connected to the support independently of the pneumatic and in position to be moved to control the closing of the circuit through 90 the contact member when the pneumatic is operated.

2. In combination with a musical instrument, a support, a primary pneumatic, a resilient electric contact member adjacent the pneumatic, and a resilient circuit controlling device mounted on the support and having a portion in position to be moved by the movable member of the pneumatic, the electric contact member being in the path 100 of movement of the circuit controlling device.

3. In combination with a musical instrument, a support, a primary pneumatic, a pair of electric contact members adjacent 110 the pneumatic, and a circuit controlling device connected to the support independently of the pneumatic and in position to be moved to control the closing of the circuit through the contact members when the pneumatic is operated.

4. In combination with a musical instrument, a support, a primary pouch pneumatic, a pair of resilient electric contact members adjacent the pneumatic, and a flat resilient metallic circuit controlling device connected to the support independently of the pneumatic and between the movable member of the pneumatic and the electric contact members and in position to be moved 120 by the pneumatic when the latter is operated, to complete contact between the contact members.

5. In combination with a musical instrument, a tension chest, a rail detachably 130

mounted therein, pouch chambers in the rail, pouches over the chambers, control ducts leading to the chambers, contact carriers mounted adjacent the respective pouches, contact members mounted in the carriers, and a circuit controlling device, for each pouch, connected to the rail and independently of the pouch and mounted in position, relative to the punch and contact members, to cause the electrical closing of 10 the latter when the former is operated.

5 In testimony whereof we affix our signatures.

JOHN GEORGE GOLL.
PAUL JOHN SOWADA.
